UNITED STATES PATENT OFFICE.

BERNARD MOEBIUS, OF CHIHUAHUA, MEXICO, ASSIGNOR OF THREE-EIGHTHS TO WILLIAM E. POPE, OF ATHENS, GEORGIA.

APPARATUS FOR THE ELECTROLYTICAL SEPARATION AND DEPOSITION OF METALS.

SPECIFICATION forming part of Letters Patent No. 310,533, dated January 6, 1885.

Application filed February 5, 1884. (No model.)

To all whom it may concern:

Be it known that I, BERNARD MOEBIUS, of Chihuahua, Mexico, have invented a new and Improved Apparatus for the Electrolytical Separation and Deposition of Metals, of which the following is a full, clear, and exact description.

This invention relates to an apparatus for refining silver and separating it from the gold, platinum, copper, lead, and other metals by means of electricity, which apparatus, if slightly modified, can be used in other electrolytical processes for the decomposition of and precipitation of metals by electricity.

Reference is to be had to the accompanying drawings, forming part of this specification, in which similar letters of reference indicate corresponding parts in all the figures.

Figure 1 is a perspective view of my new and improved apparatus for the electrolytical separation and deposition of metals. Fig. 2 is a cross-sectional elevation of the same, showing the brush-frames and conductors for supporting the anodes and cathodes lowered. Fig. 3 is a cross-sectional elevation of the same, showing the brush-frames and conductors for supporting the anodes and cathodes raised. Fig. 4 is an end view of the apparatus, showing the hoisting device. Fig. 5 is a longitudinal elevation of the apparatus, parts being broken out and others shown in section, some of the conductors supporting the anodes and cathodes being raised and others lowered. Fig. 6 is a longitudinal elevation of the apparatus, parts being broken out and others shown in section, showing the bag-frames, anodes, and cathodes raised. Fig. 7 is a sectional plan view of the apparatus in part. Fig. 8 is a plan view of the same. Fig. 9 is an enlarged detailed longitudinal sectional elevation of one of the tubs or boxes. Fig. 10 is a cross-sectional elevation of the same. Fig. 11 is a plan view of the same, showing it provided with the brushes. Fig. 12 is a plan view of the same, the brushes being omitted. Fig. 13 is a perspective view of one of the frames for holding the bags. Fig. 14 is a longitudinal elevation of the same, showing the manner in which the bags are held, parts being broken out and others shown in section. Fig. 15 is a perspective

view of the arrangement of the conductors. Fig. 16 is a longitudinal sectional elevation of one of the couplings for the conductors, parts being broken out and others shown in section. Fig. 17 is an end view of the same. Fig. 18 is a perspective view of one of the anodes. Fig. 19 is a perspective view of one of the cathodes. Fig. 20 is a side view of the clamp for holding the cathode to the conducting-wire. Fig. 21 is an end view of the same. Fig. 22 is a side view of one of the clamps for holding the anodes to the connecting-wire. Fig. 23 is an end view of the same. Fig. 24 is a longitudinal elevation of one of the brushes for cleaning the anodes and cathodes. Fig. 25 is a longitudinal edge view of two of the brushes united. Fig. 26 is a cross-sectional view of the brushes on the line *x x*, Fig. 24. Fig. 27 is a perspective view of two of the tanks, showing them located in the trough containing the water to heat the solution. Fig. 28 is a perspective view of the frame for supporting the brush-holders, this construction being a modification of the construction shown in the other figures. Fig. 29 is a perspective view of a modified construction of the anode-holder. Fig. 30 is a perspective view of two brushes, showing them provided with the improved devices for holding them on the bars, and with the improved adjusting-screw. Fig. 31 is a side view of the upper part of one of the brushes.

In refining silver with my improved apparatus the silver to be refined is cast in the form of plates A, each having an outwardly-bent lug, A', at each upper corner, as shown in Fig. 18, which plates form the anodes. The cathodes B (shown in Fig. 19) consist of a silver plate, or a copper plate covered with silver, the upper edge of which plate B is bent over the cross-piece of a U-shaped wire, B', having the upper ends of the shanks bent over horizontally, as shown.

Instead of making the anodes in the form of plates A, having bent lugs A', each anode can consist of a block or bar of silver, as shown in Fig. 29, provided in its upper edge with threaded apertures for receiving the ends of screws A², which pass freely through a bar or rod, A³, having its ends bent in the manner

shown, so as to rest on the conductors, the bent ends of the bar or rod A³ being slightly recessed to receive the conductors. The screws A² are provided at their upper ends with handles a⁴, and above the bar A³ winged nuts a⁵ are screwed on the screws A², whereby by turning the said nuts the anode can be raised or lowered. The lower parts of the screws A² are plated with gold or platinum, and when 10 screwed into the upper edge of the anode A they can be provided with a coating of varnish, to prevent their being acted upon by the solution. The anode-block can have any desired shape; but I prefer to make it in the 15 shape of a flat rectangular block, as shown in Fig. 29. The anodes A and cathodes B must be held to conducting-wires C and D, respectively, and for the purpose of holding the anodes and cathodes to the conducting-wires two 20 kinds of clamps are used, the clamps for the cathodes being shown in Figs. 20 and 21 and for the anodes in Figs. 22 and 23. The clamp for the cathodes consists of two rings, E and F, secured to each other at right angles, the bottom 25 part of one ring intersecting the upper part of the other, as shown. The upper ring, F, is provided with a downwardly-inclined notch, slot, or recess, F', for receiving the wire B of the cathodes. The said ring is also provided with a binding-screw, F², for binding the clamp on the said wire B'. The bottom ring, E, is provided with a laterally-projecting binding-screw, E', for binding the clamp 30 on the cathode-conductor D.

35 The clamp for the anodes consists of a ring or short piece of tubing, G, provided with two prongs, G', one of which is provided with a binding-screw, G², for holding the said clamp on the angular lug A' of an anode. The tube 40 or ring G is also provided with a binding-screw, G³, for binding the clamp on the anode-conductor C.

45 The anodes and cathodes form the elements of an electric battery, the solution of which battery is contained in a liquid-proof tank, box, or tub, H, of which a series are placed on a trough-shaped vessel, H', which is adapted to receive the liquid and metals which are spilled by accident. The trough-shaped vessel H' rests on a suitable base, H², made of 50 strong timbers, or constructed in any other suitable manner. On the bottom of the trough H' steam-pipes H⁴ can be arranged, the said pipes being below the tanks H. The pipes 55 are connected with the steam-inlet pipes H⁵ and exhaust-pipe H⁶. Boards H' extend from the sides of the trough to the outer sides of the tanks, to prevent the escape of steam. By admitting more or less steam into the pipes 60 H⁴, the contents of the tanks H can be heated as may be desired.

65 The tanks H can be made of wood, earthenware, or enameled metal. Enameled metal or earthenware must be used where the contents is to be heated. As shown in Fig. 1, four or more boxes or tanks H rest in one trough-

70 shaped vessel H', and the said boxes form one section, two such sections being shown in Fig. 1.

75 In each tank or box H a frame, I, Fig. 13, is placed, which is provided with four corner-standards, I', each provided in its upper end with a notch, I², adapted to receive the anode-conductors C, which conductors can be held within the notch by a pin passed transversely through apertures in the upper part of the 75 standard. The standards are united near their upper ends by horizontal rods I³, which are provided on their upper edges with upwardly-projecting pins I⁴, placed at suitable intervals. The side rods, I⁵—that is, those rods parallel 80 with the anode-conductors—support a frame, J, the end standards, J', of which are provided at the upper ends with notches J², adapted to receive the annular lugs A', formed on the upper corners of the anodes, the said 85 standards being provided at the upper ends with apertures for passing pins through them to hold the lugs of the anodes in place. The standards J' are united by two longitudinal rods, J³, which rest on the upper edges of the 90 rods I³ of the frame I. Each anode is held in a frame, J, and is surrounded by a bag, K, made of muslin or other fabric or material that will permit the solution and current to pass through it, through the seams of which 95 bag the bars J³ of the frame J are passed for the purpose of holding the bag around the frame J and the anode in the same. The frame I is surrounded by a larger bag, K', which is provided at its edges with rings or loops K², 100 through which the pins I⁴ on the bars I³ of the frame I can be passed for the purpose of holding the bag K' stretched over the frame I. The bag K' is also made of muslin, canvas, or other material which will permit the solution to pass. 105 The cathodes are suspended by means of their wires B' and the clamps E F from the negative or cathode conductors D, which run at right angles to the cathodes and parallel with the longitudinal axis of each section—that is, 110 parallel with the longitudinal trough H'. The positive or anode conductors C, which rest in the notches I² of the standards I' of the frames I, contained in the tanks or boxes H, run parallel with the conductors D, but are arranged 115 a short distance below the said conductors D and inside of the same. The conductors D are held in transverse boards or strips D', and the conductors C are held in transverse boards or strips C', the strips C' resting on the upper 120 edges of the tanks H.

125 In Fig. 15 the arrangement of the conductors is shown. The electricity enters through the positive vertical conductor C², which is connected with the first two positive or anode conductors C, which have their ends connected by a cross-bar, C³, the opposite ends being disconnected and held in a strip, C'. The ends of the cathode or negative conductors D adjoining the connected ends of the conductors C are disconnected, and are held in a strip, D'. The ends of the negative or cathode 130

conductors D above the disconnected ends of the conductors C, held in the strips C', are united by a cross-rod, D³, with which vertical rods D⁴ are connected. The positive or anode conductors C of the next tank H are connected with the vertical conductors D⁴, and the cathode or negative conductors D are arranged above and outside of them, the free ends of the said conductors D being above or near those ends of the conductors C held to the vertical conductors D⁴. The ends of the conductors D are again connected by a rod, D³, from which vertical conductors D⁴ extend downward, and so on. The conductors of any number of tanks can be connected in this manner, and the several sections can also be connected by conductors D³ in the manner shown. The current, as stated before, enters at the vertical conductor C², marked +, and leaves at the conductor D², marked -.

On the transverse rods or conductors C³ and D³, T-couplings K² are held, the transverse piece of which is made tubular, and through which the rods or conductors C³ D³ pass, the said tubular part being provided with a binding-screw, K³, for binding the tubular part on the rods C³ and D³. The vertical conductors D⁴ are screwed in the downwardly-projecting shank, as shown in Figs. 16 and 17. The same couplings are used to hold the conductors C on the vertical conductors D⁴ and for holding the transverse rods C³ on the standards C². Like couplings, K², are used to hold the rods D on the ends of the rods D³. The couplings K² held on the vertical conductors D⁴ are so arranged that the said conductors can be moved up or down in the tubular part of the T-coupling. The ends of the ropes or belts L are secured to the cathode conductors D at each end of the same by means of hooks or snaps L', or in any other suitable manner, which ropes or belts pass through eyes L², held on a bar, L³, passing longitudinally over the middle of all the tanks in one section, the ends of which bar are guided in vertical grooves M', formed by vertical strips M², secured to the inner surface of standards M, of which standards M one is arranged at each end of the section. The bar L³ is suspended from a beam or cylinder, N, by a series of ropes or chains, N', provided at their lower ends with loops N², screwed on the upwardly-projecting threaded ends of the spindles of the eyes L², which spindles are held in the desired place on the rods L³ by lock-nuts, whereby the said screw-spindles can be adjusted to project a greater or less distance from the upper surface of the said bar L³, whereby the conductors D can be adjusted to hang a certain distance below the bars L³. The beam, shaft, or roller N is journaled in the standards M, and on one end is mounted a grooved pulley, O, around which a driving chain or belt, O', passes, which also passes over a pulley, O², pivoted on the outside of one of the standards M, the shaft of the said pulley being provided with a ratchet-wheel, O³, and with a crank, O⁴, with which

ratchet-wheel a pawl, O⁵, engages. Straps P, provided with buckles P', are passed around the conductors C and D, so that when the conductors D are raised the conductors C will be suspended from the same, as is shown in Fig. 3.

In place of straps and buckles, ropes provided with adjusting devices can be provided.

In electrolytical processes—that is, where metals are decomposed or separated and deposited by electricity—the elements become polarized, which polarization is caused by the accumulation of superoxides or oxygen bubbles on the anodes and hydrogen bubbles on the cathodes, and is also caused by an irregular mixture of the solution. This irregular mixture produces solutions of metals of different specific gravity, thereby producing several layers in which each layer forms an element, the element consisting of one part of metal and two of different fluids, and these new elements produce a secondary or polarizing current. The secondary current causes a partial corrosion of the cathode and an irregular decomposition of the anode.

To prevent the above-mentioned polarization of the elements, I have provided means for agitating the liquids, these means consisting of shovels or blades K⁵, hung on the conductors C, and having their lower wider ends, K⁶, bent inward and downward, as shown in Figs. 9, 10, 11, 12, and 15. The upper end of each agitator or shovel K⁵ is connected by a cord, K⁶, with a frame, V', which frame will be described hereinafter. I prefer to use two agitators for each tank or box H, the agitators being arranged in two diagonally-opposite corners. Each element—that is, each cathode and each anode—is provided with brushes 105 for brushing the surface of the same, and thus preventing the accumulation of metals and peroxides and the accumulation of bubbles of oxygen or hydrogen on the elements. The formation of bridges or connections between the electrodes and the formation of projections on the cathodes are thus prevented, and this permits of placing the elements very close to each other without any danger of thus forming connections with each other.

The brushes Q² are shown in Figs. 24, 25, and 26. They consist of a series of rubber pins, Q, secured on rubber Q', formed around and on a steel band, Q³. The brushes are united in pairs, as shown, the bristles or pins 120 facing each other. At their upper ends the brushes of each pair are united by a screw-spindle, R, having a right and a lefthand thread, so that by turning the said spindle the upper ends of the brushes will be moved toward or from each other. The upper ends of the brush-bars are notched to receive grooved blocks R', through which the ends of the screws R pass. The blocks R' can readily be lifted from the upper ends of the brush-bars with the screws 130 R. I have provided this construction to facilitate the removal of the anodes or cathodes.

If a cathode or anode is to be removed, the blocks R' are first withdrawn, and then the cathode or anode can easily be lifted out. The screw R is provided with a disk, R^3 , for turning it to adjust the brushes a greater or less distance from each other.

I have shown the construction of the improved brush-adjusting device in Figs. 24, 25, 26, 30, and 31. Two pairs of brushes are provided for each anode and two for each cathode, so that two brushes will be on each surface of cathode or anode, the brushes being arranged as shown in Figs. 7, 10, and 11. The brushes of the cathodes and anodes are secured near their upper ends to bars or strips S and S' by V-shaped clamps S^4 , provided in their top with a slot for receiving the corresponding brush-bar, which clamps are of such width that a bar, S or S' , can be passed through horizontally and a brush vertically, the clamps being each provided with a binding-screw, S^5 , by means of which the brush can be held in the desired position on the bar S or S' . The brushes can be shifted on the bar S or S' in the direction of the length of the same. The bars S and S' are provided at their ends with screws R^2 , provided with right and left hand threaded ends, in the same manner as the screws R , previously described, which screws are used for adjusting the bars of each pair a greater or less distance from each other. The bars S and S' are parallel with the cathodes and anodes, and thus are arranged transversely to the longitudinal axis of the tanks H . The ends of the bars S rest in rabbets T , formed in the upper inner edges of the longitudinal bars of a frame, V , and the ends of the bars S' rest in rabbets T' , formed in the inner upper edges of the longitudinal bars of a frame, V' , which is located below the frame V , and is smaller, so that the inner edges of the longitudinal bars of the frame V will be flush with the vertical sides or backs of the rabbets T' , formed in the inner edge of the lower smaller frame, V' . Ropes W , W' , provided at the ends with hooks W' , pass through the eyes L^2 of the bars L^2 , and by means of the hooks W' the ends of the ropes W are secured on the longitudinal bars of the upper frames V . Straps a , provided with buckles b , are passed around the longitudinal bars of the frames V and V' ; or, in place of the straps, other adjusting devices can be used, being of about the same length as the straps P , so that if the frames V are raised the frames V' will not be raised with them until the said frames V are a certain distance above the frames V' ; or, in place of straps, the device shown in Fig. 28 can be used, which consists of bars M^8 , passed through the frames V and V' , and provided at their lower ends with buttons or heads M^9 , the said bars being provided with a series of apertures, m^8 , through which pins m^9 can be passed to support the frames V and V' at the desired elevation. Horizontal bars d are held in guides d' on the inner surfaces of the upper parts of

the standards M in such a manner that the said bars can slide in the direction of their length. The bars have one end connected by a connecting-rod, e , with a worm-wheel, e' , 70 engaging with a worm, e^2 , mounted on a shaft, e , provided with a belt-pulley, e' , over which a driving-belt, e^2 , passes, whereby by revolving the shaft e the sliding bars d will be reciprocated. For each section two bars, f , provided at their upper ends with hooks f' , are hung on the bar d , which is provided with notches d^2 in its upper edge, for receiving the hooks. The vertical bars f are united near their upper ends by a cross-bar, f^2 . The lower 80 ends of the vertical bars f are placed through vertical slots or openings g in the end bars, g , of the frames V and V' , and below the bottom of the lower frame, V , a key, h , is placed through each vertical rod f , and on these keys the bottom frame V rests. In place of the key, a transverse pin or other device may be passed through the bar f . The bars f are provided with a series of apertures, through which pins can be passed for holding the brush-frames, 90 and with them the brushes, raised when the brushes are not in use. Fig. 1 shows the frame V' of the second battery raised in this manner.

To each standard M a U-shaped frame, k , is pivoted near the upper end in such a manner that the cross-piece of the U-shaped frame will be on the outside of the standards, and the bar f^2 , uniting the upper ends of the vertical bars f , will rest on the inner end of the shanks of the frame k . A rope or chain, l , is 100 fastened to the cross-piece of the pivoted frame k , and connected with a lever, m , pivoted to the outer surface of the standard M .

To the inner end of the lever m a like rope or chain, l , is fastened, which passes over a 105 pulley, n , in the standard M , extends along under the trough H' , passes over a pulley, n , in the other standard, and then upward to the cross-piece of the frame k in the second standard. The frames V are provided in their end 110 pieces with hooks o , adapted to be passed through eyes p in the frames V' , for coupling the two frames together; or other suitable devices can be provided for holding the two frames together.

By means of the worm and worm-wheel above described the bars D are reciprocated in the direction of their length, and the vertical bars f , suspended from the reciprocating bars d , will also be reciprocated in the same 120 direction as the bars d , and will reciprocate the brush-frames V V' , suspended from the said bars f , whereby the brushes will be reciprocated parallel with the anodes and cathodes, and will brush the surfaces of the anodes and 125 cathodes, thus keeping them clean. If the elements of any one section are raised out of the tanks H , it is necessary to stop the movements of the brushes. This is accomplished by turning down the levers m , as shown in one 130 section of Fig. 1, whereby the rope l will be drawn downward and the other rope, l' , will

be drawn upward. The ropes *l* and *l'* pull downward the outer ends of the pivoted **U**-shaped frames *k*, thereby swinging the inner ends of the shanks of the said frames upward 5 and causing the said shanks to move upward, the cross-bars *f*² uniting the vertical bars *f*, whereby the hooks *f'* are lifted out of the notches *d*² in the bars *d*, so that the bars *d* can no longer reciprocate the bars *f*, as shown in 10 Fig. 6. As the brushes of the tanks of an entire section are all moved by the same frames, *V* and *V'*, all the brushes of a section can be stopped at the same time by raising the bars *f* in the manner described. It is evident that 15 if the frames *V'* are reciprocated in the horizontal plane they will swing the agitators *K*⁵ as the rope or cord *K*⁶ pulls on the upper ends of the agitators, thereby swinging them upward, and when the frame *V* returns the weight 20 of the agitators swings them down again. When the apparatus is in operation, the several parts are in the position shown in Fig. 2. If the elements are to be raised, the shaft *N* is revolved by means of the crank *O*⁴ and the 25 chain *O'*, whereby the ropes *N'* are wound on the shaft *N*, and thereby the negative or cathode conductors *D* and the upper brush-frame *V* will be raised, the vertical conductors *D*⁴ sliding in the vertical sleeves *K*² of the coupling secured on the ends of the anode-conductors *C*. The advantage of this arrangement is that when the operation is interrupted 30 the cathodes can be moved out of the bath very rapidly, and are thus protected from being acted upon or destroyed by the solution. At the same time this construction permits of immersing the electrodes as much as may be desired, whereby the density of the current can be regulated. When the belts *a* and *P* 35 are drawn taut, the positive or anode conductors *C* and the brush-frame *V'* will also be raised, as shown in Fig. 3, the frames *I* *J* and the bags *K* *K'* remaining in the tanks *H*. If the pins are placed through the apertures in 40 the upper forked ends of the standards *I'* and *J'*, respectively, of the frames *I* and *J*, the said frames and the bags will also be raised with the anodes and cathodes. If the hooks *L'* on the ends of the ropes *L*, instead of being 45 passed over the conductors *D* for the cathodes, are passed over the conductors *C* for the anodes, as shown in part of Fig. 6, and if the frames *V* and *V'* are coupled, the anodes and cathodes and both brush-frames can be raised 50 at the same time.

The troughs *H'* and the frames *I* *J*, if made of wood, are provided with several coats of graphite-paint, and powdered graphite is rubbed on them for the purpose of protecting them 55 from being destroyed by salts and acids. The sacks or bags which receive the gold, silver, &c., are saturated with a solution of coal-oil, linseed-oil, and paraffine, whereby they are made very pliable and can resist the action of the acids and salts. Those parts of the conductors which come in contact with the frames,

the tanks, the bags, &c., are provided with a rubber insulator.

The exciting-liquid consists of a solution of nitrate of silver acidulated with nitric acid, 70 to which solution quantities of nitrate of copper are added. This solution is formed in the battery if diluted nitric acid is added, and the said acid dissolves the silver and the copper in the same. By heating the solution its resistance is decreased and the decomposition of the anode is greatly facilitated. 75

The operation is as follows: A coating of oil is rubbed on the cathodes to prevent, in connection with the brushes, the deposition 80 of silver on the cathodes. The current dissolves the silver forming the anodes and precipitates it at the cathodes. Copper is dissolved also; but as it is less electro-negative, it remains in the solution if the electro-motive force of the current employed is sufficiently small. Even if some of the copper should be precipitated with the silver, it would be brushed off from the cathodes with the silver, and as it comes in contact with the 85 silver solution in the bottom of the tank it would precipitate its equivalent of silver in redissolving. According to the density of the current and the concentration of the solution, the silver is precipitated in a loose spongy 90 state or in a crystalline shape, and by the aid of the brushes drops to the bottom and is caught in the bag *K*. Lead and bismuth, as peroxides, as well as the gold, platinum, platinum metals, antimony, and, under certain 95 circumstances, a similar quantity of peroxide of silver, are precipitated at the anode, from which they are continually removed, and are caught and retained in the bags *K* surrounding the anodes. As soon as an anode-plate 100 has been dissolved it is replaced by another, so that the apparatus operates continually. If the bags *K* and *K'* of any section are to be emptied, the conductors of the said section are 105 cut out from the circuit, and the electrodes and bags are raised by means of the devices previously described, and the solution is permitted to drop off, the bags are removed and then replaced by others, the bags and electrodes are lowered, the conductors are brought 110 in circuit, and so on. The contents of the bags that have been removed are washed in hot water, and then finally pressed, dried, and melted to obtain the fine silver. 115

The principal advantages of my improved 120 apparatus are as follows: The operation is continuous and very simple, and large quantities of silver can be refined very rapidly and at a comparatively low cost, as the quantity of chemicals used is small; the apparatus requires 125 very little attention; it is not subjected to hard usage; all the parts can easily be replaced, and it is very compact; there is no need of filtering and transferring acids or handling acids or gases producing noxious and dangerous 130 gases.

I am aware that platinized carbon cathodes

are old, and I therefore do not claim such invention.

Having thus described my invention, I claim as new and desire to secure by Letters Patent—

- 5 1. In an apparatus for refining silver, the combination, with an anode formed of the silver to be refined, of a cathode provided with a coating of silver, substantially as herein shown and described.
- 10 2. In an apparatus for refining silver, the combination, with a cathode provided with a coating of silver, of an anode formed of the silver to be refined and surrounded by a bag, substantially as herein shown and described.
- 15 3. In an apparatus for separating metals by electrolysis, the combination, with a cell and a series of elements therein, of a bag surrounding the elements, and means for raising said bag out of the exciting-liquid, substantially as herein shown and described.
- 20 4. The combination, with a cell and electrodes, of brushes or scrapers contained within the cell, means for moving the brushes or scrapers along the surface of the electrodes, and means for adjusting the brushes or scrapers to suit the different thickness or position of electrodes, substantially as herein shown and described.
- 25 5. The combination, with a cell and electrodes or elements in the same, of scrapers to act within the cell and exciting-liquid on the surface of the electrodes, and means for removing the electrodes and the brushes adapted to act on the same from the cell at the same time, substantially as herein shown and described.
- 30 6. The combination, with a cell and two sets of electrodes or elements in the same, of re-

ciprocating brushes or scrapers for acting on the electrodes within the cell, and the exciting-liquid, of separate devices for operating 40 the brushes or scrapers for each set of electrodes, and means for removing each set of electrodes independently of the other, and at the same time removing the corresponding brushes or scrapers, substantially as herein 45 shown and described.

7. The combination, with a cell, of anodes and cathodes, a bag surrounding all the anodes and cathodes in one cell, and means for raising the anodes, cathodes, and bag together, 50 substantially as herein shown and described.

8. In an apparatus for the separation of metals by electrolysis, the combination, with a reciprocating frame, of pivoted agitators having their upper ends connected to said 55 frame and operated thereby, substantially as herein shown and described.

9. The herein-described anode-supporter, consisting of a bar through which screws are passed, on which screw locking-nuts are 60 mounted above the bar, the lower ends of the said screws being adapted to be held to turn in the top edge of the anode, substantially as herein shown and described.

10. In an apparatus for the separation of 65 metals by electrolysis, the combination, with a cell and its anodes and cathodes, of a bag surrounding each anode and a bag surrounding all the anodes and cathodes, substantially as herein shown and described.

BERNARD MOEBIUS.
